UNITED STATES PATENT OFFICE.

ROBERT G. BREEDING, OF CINCINNATI, OHIO.

LIQUID-FUEL-BURNING APPLIANCE.

Application filed October 13, 1920. Serial No. 416,727.

To all whom it may concern:

Be it known that I, ROBERT G. BREEDING, a citizen of the United States, and a resident of the city of Cincinnati, in the county 5 of Hamilton and State of Ohio, have invented certain new and useful Improvements in Liquid-Fuel-Burning Appliances, of which the following is a full, clear, and exact description, reference being had to the 10 drawings forming part of this specification.

My invention relates to appliances for burning liquid fuel and more particularly the heavier petroleum oils for the production of heat.

15 In the embodiment of my invention selected for purposes of illustration, the appliance is shown as employed with a domestic heating furnace, although it will be understood that the device may be used in connection with boilers or any other desired 20 type of furnace or heater.

In my copending application, Serial No. 389,701, filed June 17, 1920, is shown and claimed a liquid fuel burning appliance 25 having a particular form of burner and method of introducing the fuel counter to the air draft in which the fuel is burned and by which it is atomized. In the present application I illustrate a somewhat different 30 use of the invention from that described in the said copending application and embody in the description and claims another phase of my invention dealing with the combustion feature thereof more or less independently 35 from the system used for the injection and atomization of the liquid fuel.

Whereas I am advised it has been the practice in hydrocarbon burners in the past to introduce the flame resulting from the 40 combustion of the oil in such a way as to impinge upon the object to be heated, I have discovered on the contrary that for a perfect non-sooting and complete combustion of hydrocarbon oils it is preferable to burn 45 them entirely before the product of combustion reaches what may be termed the working point.

While my invention comprises means for the injection and atomization of hydrocarbon oil and a long fire insulated conduit 50 through which the flaming gases resulting

from ignition of the oils will pass, my entire installation might well be called a burner because until the gases resulting from the combustion have expended their flame they 55 are not allowed to emerge into the furnace or impinge upon the boiler tubes or what not.

Generally speaking, it is my object to provide an oil burning appliance for heating which will completely burn oils even of the heaviest type without the production of soot and with the maximum production of heat and this I accomplish by that certain construction and arrangement of parts to 60 be hereinafter more specifically pointed out and claimed.

In the drawings,

Figure 1 is a perspective view of a hot air furnace appliance constructed according to 70 my invention.

Figure 2 is a top plan view of the fuel consumption conduit with the top removed therefrom.

Figure 3 is a section on the line 3—3 of 75 Figure 2.

Figure 4 is a detailed longitudinal section of the fuel consumption device.

Figure 5 is an elevation of the face of the fuel nozzle.

Figure 6 is a section on the line 6—6 of 80 Figure 5.

Figure 7 is a side elevation of the nozzle.

I have shown the invention as applied to an ordinary hot air furnace, 1, the device 85 being passed through the ash door 2 of the furnace. I provide an elongated metal box 3 having suitable supports 4 and having a removable lid or cover 5 which is bolted to a flange 6 around the side of the box. I 90 prefer that the lid 5 be covered with suitable heat insulating material such as asbestos and the entire box may be so covered if desired.

For convenience in manipulation I form 95 a lid or top 5 in two sections, the section 5^a which is more likely to be removed and through which the various pipe connections pass is shown as covering the outer end of the box. The inner end of the box is not 100 provided with a lid, but is exposed so that through it the heat passes into the furnace.

I have shown as mounted on the lid proper a blower 7 operated by a motor 8, said motor 8 being controlled by any desired rheostat 9. Extending from the blower is 5 the air conduit 10 which enters at 11 preferably at about the center of the outer end wall of the box. I find it much preferable to introduce the air into the fuel consumption box or combustion chamber so that it 10 passes in a direct line through the length of such box.

The fuel inlet pipe is shown at 12 controlled by a valve 13 and a pipe 14 is employed for the introduction of gas to be used 15 in ignition. The fuel injector 15 comprises a convex faced circular metal block having a large oil orifice 16. This block is connected by an L-coupling 17 to the pipe 12. The gas pipe is preferably provided with an 20 end 18 turned to face in the direction of the air current and positioned to impinge on the face of the nozzle 19.

At the outer end of the box is a suitable plug 20 which may be removed to expose a 25 hand hole and for purposes of observation and ignition.

I may employ my device for a gas burner or combustion mechanism with most excellent results and with the production of high 30 heat, and to make a combination gas and oil device, I insert a fuel gas pipe 22 into the box and equip its end with any desired nozzle. The air from the blower will be regulatable to consume the gases and al- 35 though some of the heat generated by the combustion is lost in heating the conduit, the effectiveness of burning the gas in a highly heated conduit easily offsets the loss.

The entire box, top, bottom and side is 40 well insulated with firebricks 21 or other desired form of heat insulation, said heat insulation being omitted at the inner end of the box where the lid is also omitted leaving the opening through which the heat 45 passes into the furnace.

As so constructed the device operates as follows:—The gas is lighted at the outlet 18 by the operator and may be maintained continuously as a pilot. If very heavy oils 50 are used it may be necessary to provide some lighter hydrocarbon for the initial combustion. In such a case, it is introduced through the fuel nozzle and the blower is started up, at first slowly. The draft of air blowing 55 against the face of the burner, which is turned towards the draft instead of away from it, will atomize the fuel flowing out through the wide open nozzle and the fuel will ignite from the gas, with the air and 60 burning fuel passing together along through the combustion box or chamber.

As heat begins to be generated, the force of air from the blower and the amount of fuel, may be regulated either automatically

or by hand so as to gain the best possible 65 combustion. Of course, if light hydrocarbons are used to start the device the heavier ones will be turned into the nozzle when the appliance is sufficiently heated.

In determining proper combustion the 70 operator will observe the outlets from the box and so regulate his air and fuel that no smoke whatever or soot is projected through the combustion box.

The operation of the device is distin- 75 guishable over burners of the prior art with which I am familiar by the fact that the combustion takes place entirely within the burner structure, said structure being very highly heated by the combustion so that the 80 combustion takes place within a highly heated conduit, thereby gasifying all the constituents of the oil.

The engineering problems involved in installations of my device have to do with 85 the cross sectional area and length of the conduit, and the position of the burner, and the size of the delivery opening. The air supply should be so directed as to flow directly through the conduit and of course the 90 oil flow and air supply should be controllable.

As already stated I have in my copending application dealt more particularly with my burner, wherein among other things the 95 oil outlet is large and the incoming air spreads the oil in a film over the special shaped burner face and atomizes it thoroughly.

Leaving out of consideration, however, the 100 exact method of insuring an atomization of the oil, the device should be so constructed in the above enumerated points that while burning through its effective range, the flame should be confined substantially within the 105 conduit, with the size varying as the area of opening and heat requirements vary.

The great difficulty in most oil burning appliances, whenever heavy oils are used, and any great amount of heat is desired is 110 that smoke and soot rapidly clog up the burner and flues and insulate the parts which it is designed to heat.

I lose comparatively little heat through 115 radiation from my conduit, since this can be and is thoroughly insulated. All of the heat generated by the combustion of the gasified oils, said combustion taking place at very high temperatures, is blown against the objects to be heated, with the only effective radiant heat as distinguished from heat by convection being that coming from the luminous delivery mouth of the conduit. Of course some luminosity such as results 120 from carbon monoxide flame will escape, but this is not a flame which will carbonize.

I gain practically perfect combustion by 125 my device and the control of the air and oil

flow is very simple since by observation of the delivery mouth of the conduit, the completeness of the combustion can be determined by even the most inexperienced.

5 While speaking of air and oils in the claims I do not wish to be limited beyond the general meaning of gases and fluids, since other special gases in connection with the air and other fluids in connection with the oils are 10 desired to be covered by the use of the said terms air and oil.

Having thus described my invention, what I claim as new and desire to secure by Letters Patent, is:—

15 1. That method of burning oils for the production of heat which consists in igniting the same within an extended conduit in the path of a current of air flowing therethrough and mingling with the fuel at the 20 point of ignition, confining the flame of combustion to the conduit and delivering the products of combustion to the working point substantially free of flame.

2. That method of burning oils for the production of heat which consists in atomizing and igniting the oils in an insulated conduit in the path of a current of air flowing therethrough and mingling with the fuel at the point of ignition, confining the 30 flame of combustion to the conduit, and delivering the products of combustion to the working point substantially free of flame.

3. An oil burning appliance which consists in an insulated conduit, an oil atomizer, and a source of supply of air, said air being directed through the conduit and against the fuel at the point of ignition, and the conduit being of a length to confine the combustion resulting from the ignition of 40 the oils, said conduit having a delivery opening for delivering the products of combustion to the working point substantially free of flame.

4. An oil burning appliance comprising a long conduit insulated with fire clay material, an oil atomizer at one end of the conduit, a delivery opening at the other end of the conduit, a blower for forcing air from the burner end through the conduit to 50 the delivery end, said conduit being of a length to confine the flame resulting from combustion upon ignition of the oils substantially within the conduit.

5. An oil burning appliance comprising a conduit insulated with heat resistance material, a burner located at one end of the conduit, said burner having a large oil opening, and a distributing surface presented toward the said end of the conduit, a blower, 60 said blower being adapted to send a flow of air through the conduit directed against the said distributing surface of the burner thereby accomplishing an atomization and

said conduit being of substantial length to present an extended heated confining space 65 to the combustion of the oils whereby full gasification and combustion may take place within the conduit, said conduit having a delivery opening at the end away from the burner.

6. An oil burning appliance comprising an elongated box like structure suitably heat insulated, said box having a removable cover at the outer end thereof, and a delivery opening at the other end thereof, an oil inlet and gas inlet pipe passing into the conduit through said removable cover, and a blower having its delivery opening into the conduit directed along the axis of the conduit at the oil inlet end thereof.

7. An oil burning appliance comprising an elongated box like structure suitably heat insulated, said box having a removable cover at the outer end thereof, and a delivery opening at the other end thereof, an oil inlet and gas inlet pipe passing into the conduit through said removable cover, and a blower having its delivery opening into the conduit directed along the axis of the conduit at the oil inlet end thereof, said oil 90 inlet pipe having a burner mounted thereon within the conduit, said burner having a large oil outlet, and a spherical faced block about said opening, said spherical face being directed toward the blower delivery 95 opening.

8. An oil burning appliance comprising an elongated box like structure suitably heat insulated, said box having a removable cover at the outer end thereof, and a delivery opening at the other end thereof, and oil inlet and gas inlet pipe passing into the conduit through said removable cover, and a blower having its delivery opening into the conduit directed along the axis of the conduit at the oil inlet end thereof, said oil inlet pipe having a burner mounted thereon within the conduit, said burner having a large oil outlet, and a spherical faced block about 100 said opening, said spherical face being directed toward the blower delivery opening, and a hand hole formed within the removable cover, said hand hole having a closing plug therein.

9. An oil burning appliance which consists in an insulated conduit, an oil atomizer, and a source of supply of air, said air being directed through the conduit, and the conduit being of a length to confine the combustion resulting from the ignition of the oils, said conduit having a delivery opening for delivering the products of combustion to the working point, and a fuel gas supply pipe and burner introduced into the pipe adjacent the oil atomizer end.

10. An oil burning appliance comprising

an elongated box like structure suitably heat insulated, said box having a removable cover at the outer end thereof, and a delivery opening at the other end thereof, an oil inlet and an ignition gas inlet pipe passing into the conduit through said removable cover, and a blower having its delivery opening

into the conduit directed along the axis of the conduit at the oil inlet end thereof and a fuel gas supply pipe in addition to the ignition gas inlet pipe, said supply pipe having a burner located at the outer end of the box. 10
